UNITED STATES PATENT OFFICE

HARRISON B. WALTER, OF CHICAGO, ILLINOIS, ASSIGNOR TO CONTAINER CORPORATION OF AMERICA, OF CHICAGO, ILLINOIS, A CORPORATION OF DELAWARE

FIBER-BOARD SHIPPING CASE

Application filed July 29, 1927. Serial No. 209,224.

This invention relates to novel improvements in fiberboard shipping cases and parts thereof and consists of the matters herein-after described and more particularly pointed out in the appended claims.

The invention relates especially to shipping cases designed for shipping citrus fruit and the like, such as oranges, lemons, grapefruit. Fruit of the kind is at present largely shipped 10 in wood boxes which are 12 by 12 inches in vertical section and which are divided horizontally into two equal compartments 12 inches long so that the box includes two end panels and an intermediate dividing panel 15 each 12 by 12 inches composed of a comparatively heavy square wood frame covered by a sheet of wood veneer. This wood veneer is comparatively thin (about $\frac{1}{6}$ of an inch) and it is with great difficulty applied in building up the box because of its tendency to 20 split. With a small piece of veneer of the size used (12 by 12 inches) no matter which way the grain runs, the piece warps and cracks 25 with the result that the interior surface of the box presented by this sheet of veneer is uneven and is apt to damage the fruit. In addition, the supply of such material is failing 30 and approaching a prohibitive cost.

The object of my invention is to produce a 35 box of the kind with the parts so arranged and constructed that fiberboard may be efficiently and successfully used instead of the veneer and with the parts so arranged, constructed and correlated that fiberboard may be 40 substituted for the end and intermediate panels only, for the top only, for the top and end panels only, or the entire box, including the body, top or lid, and panels may be made of fiberboard.

The advantages of the invention will appear more fully as I proceed with my specification.

In the drawings:—

Figure 1 is a perspective view representing 45 the ordinary wooden box as it appears when packed with citrus fruit ready for shipment.

Figure 2 is a view representing a section through one panel of such box.

Figure 3 is a view representing the heavy 50 wood frame and a fiber sheet ready for assem-

bly to form one of the improved fiberboard end panels for a fruit box.

Figure 4 represents a perspective view of an end panel with the fiberboard and frame assembled and attached together. 55

Figure 5 is a fragmentary vertical section through the panel in a plane indicated by the line 5—5 of Figure 4.

Figure 6 is a perspective view of an intermediate panel made of fiberboard. 60

Figure 7 is a perspective view of the blank from which said intermediate panel is made.

Figure 8 is a perspective view of a slightly modified form of the intermediate panel made of fiberboard. 65

Figure 9 is a view representing a longitudinal section through the ordinary wooden fruit box with my improved end and intermediate panels used instead of the ordinary wood panels. 70

Figure 10 is a perspective view of a blank for use in making a fiberboard lid for a fruit box.

Figure 11 is a perspective view of the fiberboard lid when ready for application. 75

Figure 12 is a perspective view of a box having the ordinary wooden sides packed with fruit but including my improved fiberboard end and intermediate panels and fiberboard lid or cover. 80

Figure 13 is a transverse section through the box shown in Figure 12.

Figure 14 is a longitudinal section through the same. 85

Figure 15 is a perspective view of a fiberboard blank for use in making the sides and bottom of the improved fruit box.

Figure 16 is a perspective view of the aforesaid blank with reinforcing and strengthening wood cleats which are used in the improved fiberboard box body. 90

Figure 17 is a perspective view of the improved fiberboard box body as it appears when set up in box form. 95

Figure 18 is an end view of the fiberboard box body illustrating the same as it appears when collapsed ready for shipment.

Figure 19 is a perspective view of the improved fiberboard fruit box as it appears when 100

packed with all of its parts including the improved fiberboard members.

In the packing of citrus fruit for shipment it is essential, in order that it may be accepted by those to whom it is shipped as fresh, that it be so tightly packed in the box that the lid will be bent upwardly at the middle, leaving the fruit exposed in the gaps thus left between the top edges of the sides of the box and the lid or cover. This is illustrated in Figure 1 wherein is shown the usual wood veneer box 20 packed with some such citrus fruit as oranges or grapefruit. The fruit is packed in the box body 21 and is so filled that the level of the fruit projects considerably above the top edges 22 of the box. Pressure is then applied and the lid 23 is nailed down against the tops of the end panels 24. As illustrated in that view, the fruit appears in the gaps 25. If the fruit does not thus appear and if the lid is not forced upward by the fruit as shown in the drawing, the dealers who receive the fruit will think that the fruit has been dried out in transit, as a result of which drying out the lid has been permitted to close down on the intermediate panel 24^a so as to close the gaps 25.

In Figure 2 is illustrated the splitting and warping which occurs in the case of the wood veneer sheets now used in making the end and intermediate panels of the box. These panels comprise a rectangular frame 26 made of four strips morticed together at the corners of the frame and of a wood veneer sheet 27. The objectionable warping and splitting of the wood veneer 27 is clearly illustrated in Figure 2. This warping and splitting not only exposes the fruit to damage from the outside but also subjects the fruit adjacent the panel to scarring and bruising by the irregularly distorted and broken parts of the sheet as the box is shifted about and jarred during its handling and shipment.

In Figures 3, 4 and 5 is illustrated the new fiberboard panel which is to be substituted for the old veneer panel. 28 indicates the frame which is the same or similar to the frames heretofore used. 29 indicates the sheet of fiberboard. These fiberboard sheets are beveled at one edge 30 which is used as the top edge so that there may be no sharp corner presented at the top edge of the panel to bruise or mar the fruit. The sheets 29 are made at the plant and are then shipped flat with others to the point of packing the fruit, where the wood frames 28 are made up and used in making the end panel 31, which is shown complete in Figure 4. The fiberboard sheet 29 is attached to the panel by means of nails 32. These end panels when made are much superior to the old veneer panels. They will not warp or split and they always present perfectly smooth surfaces

against the fruit which comes in contact with the inner face of said panels.

In Figure 6 is shown an intermediate panel of the fiberboard type. This comprises a wood frame 33 similar to the frames 28 of the end panels and a fiberboard blank 34. Said blank when made in its preferred form comprises a length of blank 34^a which includes sections 35 each substantially equal to the area of the frame 33 and an intermediate part 36 separated from the sections 35 by creases 37, 37. Said intermediate part is of a width equal to the thickness of the members constituting the frame 33 and the blank by the construction thus described is capable of being applied to the frame 33 with the sections 35, 35 nailed respectively to the opposite faces of the frame 33 and with the intermediate section 36 engaged against one edge (the top edge) of the frame 33. The creases 37 present beveled edges 37^a, 37^a at the top of the panel which prevent sharp corners from being present in the neighborhood of the top of the intermediate panel to bruise the fruit.

In Figure 8 a slightly modified form of the intermediate panel is shown. In this case two sheets 38, 38 of fiberboard of the area of the frame 33^x are made. These sheets are formed with beveled edges 39 so that when applied and nailed to the opposite faces of the frame 33^x there is presented an intermediate panel with beveled edges along its top.

The fiberboard end panels and intermediate panel may be used with the ordinary wooden boxes, as shown in Figure 9 wherein a wooden box with wooden bottom 39, wooden sides 40 and wooden cover or lid 41 is shown with the fiberboard end panels 31 and the fiberboard intermediate panel 33^a.

In Figures 10 and 11 is shown a fiberboard cover or lid and the fiberboard sheet from which it is made. 42 indicates a fiberboard sheet, the main length of which 43 is of the length and width of the box to which the lid is to be applied. 44 indicate extensions which are separated from the main length 43 by creases 45. To form the lid, the extensions 44 are folded back upon the main length 43 of the blank as shown in Figure 11, and are held in that position by narrow, longitudinal, wood strips 46, each of the length of the box and lid. Said strips 46 are attached to the margins of the main length 43 of the blank by means of staples or otherwise with their ends lapping upon and holding down the folding extensions 44. The said fiberboard extensions 44 reinforce and strengthen the ends of the fiberboard cover thus made and the wood strips 46 reinforce and stiffen the lateral margins of the fiberboard lid which is indicated as a whole by the numeral 47.

In Figure 12 is shown a box still having the old wood sides 48 and bottom 49 but being

made with the fiberboard end panels 31 and intermediate panel 33^a and with the fiberboard lid or cover 47.

After the fruit has been pressed into the box in the manner heretofore described, the fiberboard lid or cover 47 may have its ends nailed to the end panels as illustrated, in the same manner as has heretofore been customary with the wool veneer lids. The wood strips 46 at the lateral margins of the fiberboard lid permit the lid to yield upwardly in the neighborhood of the intermediate panel 33^a so as to leave the desired gaps exposing the fruit, as illustrated in Figures 12, 13 and 14; and the stiffening in the lateral margins of the fiberboard lid provided by said strips permit this yielding without tearing or destroying the edges of the fiberboard sheet included in the lid. The reinforcing extensions 44 on the lid give ample grip for the nails by means of which the ends of the fiberboard lid are secured to the end panels.

In Figures 15 to 18 inclusive is shown the fiberboard body. This is made from a blank of fiberboard 50 (Figure 15) which is cut and creased to provide a bottom section 51, two side sections 52, 52 and foldable flanges 53, 53,—said several sections being divided by creases 54 which are located between the several sections. The body blank is reinforced by means of narrow wood strips 55, 55 nailed upon the outside surface of the fiber sheet (the one opposite to that uppermost in Figure 15) along the nearer edges of the two intermediate creases and like wood strips 56, 56 engaged between the marginal parts of the side sections 52 and the flange extensions 53, 53 which are folded back in the reverse direction to the crease as shown in Figure 16. The wood strips 55, 55 provide bottom rails to raise the box bottom from the floor or other surface on which the box rests. The wood strips 56 heavily reinforce the top lateral edges of the box body. These features of the construction are illustrated in Figure 17 where the box body part is shown set up with the bottom section 51 horizontal and the two side sections 52, 52 in vertical position.

The body fiberboard section may be shipped flat, folded by reason of the creases 54 in the manner shown in Figure 18. When shipped they may be without the wood strips which may be applied at the place of packing the box.

In Figure 19 is shown a box 57 in which all the parts are made of the fiberboard body 52^x, the fiberboard end panels 31, the fiberboard intermediate panel 33^a and the fiberboard lid or cover 42.

In forming the box the fiberboard body 52^x is set up as shown in Figure 17 and the end panels and intermediate panels nailed thereto in an obvious manner. The box is then ready for packing. The fruit is packed therein as in the case of the wood boxes and

the lid member 57 applied and nailed to the fiberboard end members 31. The gap between the lid and the top edges of the sides is produced by the upward pressure of the fruit and is permitted by the structure of the box and its parts. The wood strips 56 at said edges give the top edges the necessary strength to prevent breaking or distortion at the top edge of the box.

The sides of the body member are provided with ventilating openings 58.

I claim as my invention:

A fiber board shipping case for citrus fruits and the like, comprising a body made from a blank of fiber board creased to provide the bottom and two sides of the case with extensions at the ends of the blank folded back upon itself, longitudinally extending wood strips secured to the bottom section of the blank along its lateral margins, and wood strips secured between said extensions and the adjacent parts of said blank; end panels each comprising an open wood frame and a fiber board sheet beveled at its top edge and nailed to said frame, an intermediate panel comprising an open wood frame and a fiber board sheet folded to cover opposite faces of said frame and nailed thereto, and a lid consisting of a fiber board sheet bent back upon itself at its ends and of wood strips extending along and secured to the margins of said blank with their ends engaged upon said folded extensions, said parts being all secured together in the manner described.

In testimony that I claim the foregoing as my invention, I affix my signature this 15 day of July, A. D. 1927.

HARRISON B. WALTER.
